UNITED STATES PATENT OFFICE.

AUGUST SUNDH, OF HASTINGS-ON-HUDSON, NEW YORK.

FLEXIBLE TUBING.

Application filed December 20, 1919. Serial No. 364,295.

To all whom it may concern:

Be it known that I, AUGUST SUNDH, a citizen of the United States, and a resident of Hastings-on-Hudson, in the county of West-
chester and State of New York, have invented certain new and useful Improvements in Flexible Tubing, of which the following is a specification.

My invention relates to flexible, metallic tubing constructed of corrugated, metal strips helically wound to form a corrugated, flexible, metallic tube.

In the present invention I have provided an inner, metallic member comprising a helically wound, corrugated, metal strip which when wound forms a metal tube having inwardly and outwardly extending loops. I envelop this member in a helically wound, metal strip which when wound also forms a corrugated tube having inwardly and outwardly extending loops. The adjacent edges of the strips are attached to each other by solder which may be fused as the tubing is being formed or applied in any other suitable way, and also the loops of the two members are secured to each other at all points by solder or other fusible, metallic binder.

In the accompanying drawings,—

Fig. 1 is a part sectional elevation of an embodiment of my invention;

Fig. 2 is an enlarged, sectional, elevational view of the tubing of Fig. 1; and

Fig. 3 shows diagrammatically a modification of the tubing of Figs. 1 and 2.

Referring to the drawings in detail, 1 designates a corrugated, metal strip helically wound to form inwardly extending loops 2 and outwardly extending loops 3. Enveloping the strip 1 is a helically wound, metal strip 4, this strip being corrugated and wound to form outwardly extending loops 5 and inwardly extending loops 6. The adjacent edges of the helically wound strip 1 approach each other at the point 7 which is beneath the base of the inwardly extending loops 6 of the outer strip 4. The adjacent edges of the outer strip approach each other at the point 8, immediately above the outwardly extending loops 3 of the inner member. The inwardly and outwardly extending loops of the two members 1 and 4 are shaped so as to conform to each other and are secured to each other at every point by a fusible, metallic binder 9 such as solder fused during the forming of the tube, this binder functioning not only to secure the

two strips to each other but also to secure the adjacent edges of each strip to each other at the points 7 and 8.

Other methods of securing these strips to each other may be employed such as, for example, coating the surfaces of each strip to be joined with solder, then bringing the two strips together and applying heat to fuse the solder, thereby securely joining the two strips to each other at all points to form a unitary flexible tubing.

In the embodiment of my invention illustrated in Fig. 3 I have shown diagrammatically a flexible tubing comprising an inner flexible, metallic strip 10 helically wound to form inwardly and outwardly extending loops 11 and 12, respectively. This strip 10 is enveloped by a helically wound, metal strip 13 having inwardly and outwardly extending loops 14 and 15, respectively. Enveloping the strips 11 and 13 is a helically wound, metal strip 16 having inwardly extending loops 17 and outwardly extending loops 18. The inwardly and outwardly extending loops of all three members are secured to each other at all points by a fusible, metallic binder such as solder as in the case of the tubing of Fig. 1. It will be noticed that the adjacent edges of the inner strip 11 approach each other at the point 19; the adjacent edges of the strip 13 approach each other at the point 20 which is in a different part of the loops of the tubing as a whole; and that the adjacent edges of the strip 16 approach each other at the point 20 at the base of the inwardly extending loops. In other words, the points of approach of the adjacent edges of the strips are staggered so as not to weaken the tubing.

It will be seen from the foregoing that I have provided what may be considered as a double-walled, flexible, metallic tubing, the corrugations or inwardly and outwardly extending loops of each wall being secured to each other at all points by means of a fusible, metallic binder whereby leakage of the tubing, due to leaky joints, is eliminated, the flexibility of the tubing, however, being maintained.

I am aware that flexible tubing has been made by merely corrugating a metal tube or by helically winding a corrugated, metal strip to form a tube. Both methods, however, have their limitations in that in the first instance the length of tubing which may

be made by merely corrugating a metal tube is limited whereas in the second instance where a helically wound, corrugated, metal strip is used, the tubing becomes leaky at 5 the joints, that is to say, where the adjacent edges of the strip are welded to each other.

In the present instance it will be noted 10 that I have provided a tube wherein leakage, due to ruptured joints, cannot occur; 10 also that in the present tubing the walls are absolutely uniform throughout, the fusible metallic binder for securing the loops of both members to each other extending to all points of the loops.

15 What I claim as new is:

1. The method of making a flexible metallic tubing consisting in helically winding a corrugated metal strip to form a tube having inwardly and outwardly extending 20 loops, winding a second corrugated metal strip about the first strip so as to bring the inwardly and outwardly extending loops of the one strip in register with the similar loops of the other strip to form a double 25 walled tube, and permanently and rigidly uniting the face of the inner strip to the adjacent overlying face of the outer strip throughout their entirety.

2. A flexible metallic tubing comprising

a metal tube composed of a helically wound 30 corrugated metallic strip surrounded by a corrugated metal strip wound helically so that the loops thereof register with the loops formed by the corrugations on the inner tube, the two strips being permanently 35 united to each other throughout their entire length.

3. A flexible, metallic tubing comprising a corrugated metal strip helically wound to form inwardly and outwardly extending 40 loops, the adjacent edges of said strip approaching each other at the base of the inwardly extending loops, a helically wound, corrugated, metal strip enveloping the first-named strip and having inwardly and outwardly extending loops, the adjacent edges of the enveloping strip approaching each other at the base of the outwardly extending loops of said strip, and a fusible binder 45 between adjacent edges of both strips and between the walls of the inner member and the enveloping member for binding the two metal strips to each other at all points and to prevent separation of the adjacent edges of each strip. 50

This specification signed this 17 day of December, 1919.

AUGUST SUNDH.
